YARN-ADVANCING REEL

Robert H. Stafford, Richmond, Va., assignor to
E. I. du Pont de Nemours & Company, Wil-
mington, Del., a corporation of Delaware

Application March 23, 1946, Serial No. 656,625

4 Claims. (Cl. 28—71.7)

1

This invention relates to a yarn-advancing apparatus, and more particularly to a yarn-advancing reel for continuously advancing yarn in the general form of a helix.

An object of this invention is to provide a new and improved yarn-advancing apparatus.

Another object of this invention is to provide a yarn-advancing reel in which a yarn is continuously advanced thereover in a generally helical form and which is simple to construct and operate.

Other and additional objects will become apparent hereinafter.

The objects of this invention are accomplished, in general, by helically winding a yarn around a reel having a set of fixed yarn-carrying bars concentrically mounted about and rotatable with the central reel spindle and a set of yarn-carrying blades disposed alternately between the fixed bars and carried by discs which are so mounted in the reel that, upon rotation thereof about the reel spindle, the discs will revolve in a perpendicular plane that is skewed with respect to a plane perpendicular to the axis of the spindle.

The yarn-carrying blades are supported in slots of two parallel discs by a ball-and-socket support so that, as the reel revolves, the blades will continually change their angular position with respect to the slotted discs.

The slotted discs are mounted on and rotate about a stationary eccentric sleeve, the bearing surfaces of which are eccentric with respect to the axis of the spindle and so skewed as to cause the discs to revolve in a vertical plane that is skewed with respect to a plane perpendicular to the axis of the spindle. Due to the construction and arrangement of the parts of the reel, upon rotation of the spindle a fixed bar at one point on the circumference of the reel contacts a blade and causes the slotted discs to rotate. This point of driving contact between a fixed bar and a blade occurs only at one position on the periphery of the reel and shifts during rotation to successive bars and blades. During one-half of a revolution, the blades project beyond the fixed bars into yarn-carrying position and move laterally in the direction of feed of the yarn to advance the yarn across the reel. During the remaining one-half of the revolution, the blades are in a retracted position below the fixed bars and move laterally in the direction opposite to that of the yarn travel for a distance equal to that traveled by the blades in yarn-advancing position. When the reel is viewed from an end thereof, it will be observed that the blades travel in an elliptical path.

The present invention will be more clearly understood by reference to the following detailed description when taken in connection with the accompanying drawings, in which:

2

Figure 1 is an end view of the reel of the present invention;

Figure 2 is a section taken on line 2—2 of Figure 1;

Figure 3 is a section taken on line 3—3 of Figure 1; and

Figure 4 is a section taken on line 4—4 of Figure 3.

Referring now to the drawings wherein like reference numerals designate like parts, the reference numeral 10 designates each of a plurality of longitudinally extending spaced bars arranged in the form of a cylinder. One end of each bar 10 is secured to a circumferential flange 12 and the other end is secured to the inner face of a solid head 14. The solid head 14 has an inwardly extending elongated hub 16 which screws on, as indicated by the reference numeral 18, to one end of a horizontal spindle 20, which is driven in any suitable manner by means not shown.

The bars 10, together with the circumferential flange 12 and the solid head 14, constitute a rigid cylindrical cage assembly in which the bars are fixed and disposed concentrically about the spindle 20. Upon rotation of the spindle 20, the rigid cage will be rotated and the fixed bars 10 will revolve therewith in a fixed circular path about the axis of the spindle 20.

The flange 12 imparts rigidity to the cage and especially to the fixed bars 10. It also prevents the yarn from getting back of the reel during the threading operation.

A stationary sleeve 22 is positioned on the hub 16. The bore of the sleeve 22 is such that when the sleeve is disposed in position on the hub, it (the sleeve 22) will be skewed with respect to the axis of the spindle 20. The sleeve 22 is also provided with two spaced eccentric bearing surfaces 24.

A disc 30 is (freely) rotatably positioned on each bearing surface 24. The discs 30 are in spaced and parallel relationship with respect to each other. Each of the discs 30 is provided with slots 36, and the discs 30 are so positioned on the sleeve 22 that the slots in one disc are aligned with corresponding slots in the other disc. In each pair of aligned slots, there is positioned a yarn-carrying blade 40 which is supported by a ball-and-socket arrangement, as will now be described.

Each blade 40 is provided with a pair of holes in which a cylindrical ball 42 is positioned. The diameter of the balls 42 is greater than the thickness of the blades 40, with the result that spherical surfaces of the balls 42 project beyond the side surfaces of the blades 40. These projecting spherical portions are positioned in spherical counter-bores which act as sockets for the projecting spherical surfaces and which are formed 60 in the sides of the slots on the center line of the

discs. The sides of the slots 38 in the discs 38 are beveled in such a manner as to allow the blades to swing in perpendicular planes about the center of the spherical counter-bores.

Upon rotation of the reel, as will be hereafter more fully described, the blades 40 continually change their angular position with respect to the slotted discs 38 since the bearing surfaces 24 of the sleeve 22 are eccentric with respect to the axis of the spindle 20, and, since the sleeve 22 is skewed with respect to the axis of the spindle, upon rotation of the discs 38 they will revolve in a vertical plane that is skewed with respect to a plane perpendicular to the axis of the spindle. A shoulder 44 and a thrust collar 46 threadedly disposed on the sleeve 22 maintain proper spacing between the discs 38. The sleeve 22 is maintained stationary and kept from rotating by tongs 48 which engage grooves in a mating part of the support, generally designated by the reference numeral 50, which carries the reel. The slotted discs 38, together with the blades 40 carried thereby and the sleeve 22, constitute a non-rigid reel assembly.

From the foregoing description, it is apparent that as the slotted discs are revolved on the eccentric sleeve 22, the blades 40 remain parallel but vary their distance from the center line of the spindle 20, and they also oscillate longitudinally with respect to the bars 10. The eccentric bearings 24 are of such design that, during one-half of a revolution of the reel, a yarn will be carried and advanced by the blades 40 which project beyond the fixed bars 10 and move laterally in the direction of the yarn feed. During the remaining half of the revolution, the blades 40 are below the fixed bars 10, whereby the yarn is carried by such fixed bars and the blades are moved laterally, in the direction opposite to the direction of yarn travel on the reel, for a distance equal to that which it (the blade) moved during the yarn-advancing operation.

The non-rigid assembly is driven by the rigid assembly. Due to the construction and arrangement of the parts of the reel, upon rotation of the spindle 20 the fixed bars 10 will be revolved in a circular path about the center axis of the spindle 20. During such operation, at one point on the circumference a fixed bar 10 contacts a blade 40, causing the discs 38 to rotate on the sleeve 22. This point of driving contact between a fixed bar 10 and a blade 40 occurs at one position on the periphery of the reel and shifts during rotation to successive bars and blades.

The increment of the yarn advancement over the reel or the magnitude of the pitch of the advancing yarn is determined by the degree to which the discs 38 are skewed.

The balls 42 can be either separate or integral parts of the respective blades 40.

In assembling the reel after the non-rigid reel assembly has been assembled, it is inserted in the rigid cage by sliding the sleeve 22 over the elongated hub 16. Thereafter, the hub 16 is slid on the spindle 20 and rotated by hand until the spindle 20 is in driving position.

Though in the embodiment hereinbefore described the eccentric bearings 24 are of such design that during one-half (180°) of the revolution of the reel the yarn will be carried and advanced in the direction of yarn feed by the blades 40 and during the remaining half (180°) of the revolution the blades 40 are out of contact with the yarn and the latter is carried by the fixed bars 10, it is to be understood that the invention

is not restricted thereto. By appropriate design of the eccentric bearings 24, the movable blades 40 can be made to carry and advance the yarn for more or less than 180° of the revolution of the reel and the fixed bars carry the yarn for the remainder of the revolution of the yarn. Further, by appropriate design of the eccentric bearings 24, the fixed blades 10 and the movable blades 40 can be made to alternately carry the yarn a plurality of times during a single revolution of the reel. In the latter embodiment, the portions of the revolution of the reel wherein the movable bars carry the yarn can be equivalent to or greater or less than those wherein the fixed bars carry the yarn.

The reel can be used for continuously advancing yarn in the general form of a helix. The yarn can be processed as desired while on the reel. Thus, for example, if the yarn is made by the viscose process, the support 50 may constitute a part of the frame of the spinning machine and the yarn may be washed, desulfured, bleached or dried during its passage across the reel. If desired, the yarn can be stretched while still wet with coagulating bath liquor or under the influence of hot water by making the blades 40 progressively deeper toward the yarn wind-off end and making the helices larger at that end. Alternatively, the blades 40 may be made progressively smaller toward the yarn wind-off end to allow for shrinkage during appropriate treatments, such as desulfuring or drying.

Though the invention has been specifically described in connection with a reel of the cantilever type, it is to be understood that the invention is not restricted thereto. The invention can be applied to reels that are supported at both ends.

Since it is obvious that many changes and modifications can be made in the above-described details without departing from the nature and spirit of the invention, it is to be understood that the invention is not to be limited thereto except as set forth in the appended claims.

I claim:

1. In a yarn-advancing reel, a rotatable spindle, a set of spaced fixed yarn-contacting bars arranged concentrically about and rotatable with said spindle, a set of yarn-contacting blades disposed alternately between said fixed bars, a stationary eccentric sleeve disposed on said spindle in a skewed position with respect to the axis of said spindle, a pair of slotted parallel spaced discs rotatably mounted on said sleeve with the slots of one disc in alignment with the corresponding slots in the other disc, and means mounting a blade in each respective pair of aligned slots to permit said blades to continually change their angular position, during revolving of the reel, with respect to the slotted discs, the means for mounting each of said blades comprising a pair of spherical balls carried by each blade, the spherical surfaces of said balls projecting from the sides of said blade being positioned in complementary shaped sockets formed in the sides of said slot.

2. In a yarn-advancing reel, a rotatable spindle, a set of spaced fixed yarn-contacting bars arranged concentrically about and rotatable with said spindle, a set of yarn-contacting blades disposed alternately between said fixed bars, a stationary eccentric sleeve disposed on said spindle in a skewed position with respect to the axis of said spindle, a pair of slotted parallel spaced discs rotatably mounted on said sleeve with the slots of one disc in alignment with the corre-

sponding slots in the other disc, and means mounting a blade in each respective pair of aligned slots to permit said blades to continually change their angular position, during revolving of the reel, with respect to the slotted discs, the means for mounting each of said blades comprising a pair of spherical balls positioned in holes in said blade with the spherical surfaces of said balls projecting from the sides of said blade, the spherical projecting surfaces of each ball being positioned in complementary shaped sockets in the sides of the slot.

3. In a yarn-advancing reel, a rigid cylindrical casing having a plurality of spaced fixed yarn-contacting bars extending longitudinally about the periphery and concentrically arranged about an inwardly extending hub, a rotating spindle disposed in and secured to said hub, an eccentric sleeve mounted on said hub in a skewed position with respect to the axis of said spindle, a pair of spaced slotted discs rotatably mounted on said sleeve with the slots of one disc being in alignment with the corresponding slots in the other disc, and means mounting a yarn-contacting blade in each respective pair of aligned slots to permit said blades to continually change their angular position during revolving of the reel with respect to the slotted discs, the means for mounting each of said blades comprising balls carried by each of said blades with the spherical surfaces of said balls projecting from the sides of each blade positioned in complementary shaped sockets formed in the sides of said slots.

4. In a yarn-advancing reel, a solid head, an elongated hub extending inwardly from said head, a plurality of fixed yarn-contacting bars arranged in spaced relationship about the periphery of said head and concentrically about said hub, a rotating spindle disposed in and secured to said hub, an eccentric sleeve mounted on said hub in a skewed position with respect to the axis of said spindle, a pair of spaced slotted discs rotatably mounted on said sleeve with the slots of one disc being in alignment with the corresponding slots in the other disc, and means mounting a yarn-contacting blade in each respective pair of aligned slots to permit said blades to continually change their angular position during revolving of the reel with respect to the slotted discs, the means for mounting each of said blades comprising balls carried by each of said blades with the spherical surfaces of said balls projecting from the sides of each blade positioned in complementary shaped sockets formed in the sides of said slots.
